(57) **CLAIM**

The ornamental design for a dowel tube, as shown and described.

DESCRIPTION

FIG. 1 is a perspective view of the dowel tube of the present invention showing my new design;

FIG. 2 is a top plan view thereof;

FIG. 3 is a left side view thereof;

FIG. 4 is a front view thereof;

FIG. 5 is a rear view thereof;

FIG. 6 is a right side elevational view thereof; and,

FIG. 7 is a bottom plan view thereof.

The broken lines in the drawings illustrate portions of the dowel tube and form no part of the claimed design.

The dowel tube is shown with a symbolic break in its length. The appearance of any portion of the article between the break lines forms no part of the claimed design.
